Attorney-

UNITED STATES PATENT OFFICE.

ALBERT GEORG KOECHLIN, OF BASEL, SWITZERLAND.

WEFT-SPOOL CHANGER FOR WEAVING-LOOMS.

1,321,315.

Specification of Letters Patent.

Patented Nov. 11, 1919.

Application filed September 11, 1919. Serial No. 323,167.

To all whom it may concern:

Be it known that I, ALBERT GEORG KOECHLIN, a citizen of the Swiss Republic, and resident of Basel, Switzerland, factory director, 5 have invented new and useful Improvements in Weft-Spool Changers for Weaving-Looms, of which the following is a full, clear, and exact specification.

In specification of the U. S. patent application Ser. No. 294030 is described a weft spool changer for weaving looms wherein the pusher or transfferer, mounted on the lay, is always in coöperative relationship with an arm adapted to depress it for introducing the spool into the shuttle, and wherein the mechanism for operating this arm is so arranged that the pusher may be depressed for introducing a fresh spool, not only, as previously, before the dead point 20 position of the lay, but also in any later position up to the moment when the throw of the shuttle begins.

With this arrangement it may happen that the new weft spool is not in correct position 25 for operation of the pusher, in which event the pusher, its driving mechanism or some other part of the loom may be damaged.

The present invention relates to an improvement to the weft spool changer of the 30 above kind, whereby this disadvantage is avoided. For this purpose, the mechanism for operating the pusher comprises an arm made in two parts coupled together by a yielding coupling, so that, normally, the arm 35 depresses the pusher for introducing a new weft spool, but when an obstruction occurs the coupling yields and damage by thrust upon the pusher is avoided.

The accompanying drawing illustrates the 40 invention.

Figure 1 is a side elevation, similar to Fig. 1 of the aforesaid specification.

Fig. 1^a shows a detail of Fig. 1;

Fig. 2 is a side elevation and

45 Fig. 3 an end elevation of the arm operating the pusher;

Fig. 4 is a partial section on line A—B of Fig. 2.

As in the construction described in the 50 aforesaid specification, a weft thread control determines the change of weft spool when there is failure of the weft thread. When this happens the weft control fork 5 is engaged in the known manner by the oscillating lever 7 (Fig. 1), and the latter pushes in 55 its outward path the rod 2 against a spring

(not shown) and acts through this rod on a lever arm 8 fixed to the usual spool changing control shaft 13, thereby starting the operation of the change mechanism on the 60 other side of the loom.

The turning movement of shaft 13, caused by the thrust of rod 2, is transformed on the other side of the loom, by means of an arm 14^a on the shaft 13, into rectilinear movement 65 of a toothed rod 14, which through a pinion 15 and an arm 16 connected with a crank pin on the pinion, moves a lever 17 and thus engages the movable sleeve 18 of a clutch 19 on the bearing pin 21 (Fig. 1^a). The sleeve 18 carries an arm 22 on which is a roller 23 for 70 coöperation with a cam disk 24 but normally out of the path of the cam 31 thereof. The counter part 20 of the clutch 19 has an arm 25 which extends over an adjustable cross-head 26 (Fig. 1) on the pusher 27. The latter moves to and fro in space with the lay 28, in the top part 29 of which it is mounted to slide up and down, being normally held up by springs 30. It moves with the lay, unhindered by the arm 25. When, however, the clutch 18—20 is engaged, the roller 23 comes into the path of the cam 31 of the disk 24 and is raised so as to depress the arm 25 and therefore the pusher 27 which expels from 80 the free end of an inclined channel-like spool magazine a loaded spool into the shuttle, the latter having in the meantime arrived beneath the pusher. The cam disk 24 and the parts coöperating therewith are so arranged that the introduction of a new spool occurs during a period of time within which the driving shaft of the lay (crank shaft) makes a quarter revolution and that the depression of the pusher begins approximately 85 when the lay is at its forward dead point and ends when, after this dead point has been passed, the shuttle throw begins. This condition is here quite possible since the pusher always shares the movement of the 90 lay. The period of time of the action of the pusher may be adjusted within certain limits by adjusting the cam disk 24 with its cam 31, so that the feed of a new weft spool

95 may be made to occur not only, as previously, before the forward dead point position of the lay, but also at this position and after it, up to the beginning of the shuttle throw.

According to the present invention, the 100 arm 25 for operating the pusher is made in two parts (Figs. 2-4) connected together by a flexible coupling. The latter

comprises two disks 40, 41, of which one is rigidly connected with one part of the arm 25 and the other with the other part. One of the disks carries two convex nipples 42 adapted to engage in two cavities on the other disk, the engagement being maintained by a spring 43 urging the two disks together.

Normally the arm 25 can operate the pusher to introduce a new weft spool, since the coupling lends the arm sufficient rigidity for the purpose. If, however, there is an obstruction to the pusher owing to incorrect feed of spools, the coupling 40, 41 yields and the arm 25 bends, damage being thus avoided.

Any other suitable coupling for the parts of the arm may be substituted for that described.

20 What I claim is:

1. In an automatic weft replenishing loom, an oscillating lay, a shuttle arrangement, a pusher for introducing a full weft spool into the empty shuttle, said pusher being movable with the lay and further capable of up and down movement relatively to the lay, a two-part actuating arm adapted by one of its parts to depress the pusher for a weft spool changing operation and to remain during the travel of the pusher in coöperative relationship therewith, a yielding coupling yieldingly connecting the two parts of said actuating arm, an independent device for automatically operating the said actuating arm on its other part, and weft failure detecting

means to set said operating device into operation when the weft fails, substantially as and for the purpose described.

2. In an automatic weft replenishing 40 loom, an oscillating lay, a shuttle arrangement, a pusher for introducing a full weft spool into the empty shuttle, said pusher being movable with the lay and further capable of up and down movement relatively to the lay, a two-part actuating arm 45 adapted by one of its parts to depress the pusher for a weft spool changing operation and to remain during the travel of the pusher in coöperative relationship therewith, a yielding coupling yieldingly connecting the two parts of said actuating arm, an independent device for automatically operating the said actuating arm on its other part, and weft failure detecting 50 means to set said operating device into operation when the weft fails, said yielding coupling comprising two disks rigidly connected with the parts of the said actuating arm respectively and engaged with each 55 other under spring action by means of convex nipples and concave cavities, substantially as and for the purpose described.

In witness whereof I have hereunto signed my name this 22nd day of August 65 1919, in the presence of two subscribing witnesses.

ALBERT GEORG KOECHLIN.
